DESIGN FOR A PEN OR SIMILAR ARTICLE

Edmund A. Pontius, Jr., Memphis, Tenn.

Application October 22, 1941, Serial No. 103,866

Term of patent 3½ years

To all whom it may concern:

Be it known that I, Edmund A. Pontius, Jr., a citizen of the United States, residing at Memphis, in the county of Shelby and State of Tennessee, have invented a new, original, and ornamental Design for a Pin or Similar Article, of which the following is a specification, reference being had to the accompanying drawing, forming part thereof.

I claim:

The ornamental design for a pin or similar article, substantially as shown and described.

EDMUND A. PONTIUS, JR.
